M. ROTHBART

LAMP BRACKET

Filed April 27, 1927

Inventor:
Max Rothbart
By Clarence J. Loftus
Febby.

UNITED STATES PATENT OFFICE.

MAX ROTHBART, OF CHICAGO, ILLINOIS, ASSIGNOR TO REMBRANDT LAMP CORPORATION, OF CHICAGO, ILLINOIS, A CORPORATION OF ILLINOIS.

DESIGN FOR A LAMP BRACKET.

Application filed April 27, 1927. Serial No. 21,755. Term of patent 3½ years.

To all whom it may concern:

Be it known that I, MAX ROTHBART, a citizen of the United States, residing at Chicago, in the county of Cook and State of Illinois, have invented a new, original, and ornamental Design for a Lamp Bracket, of which the following is a specification, reference being had to the accompanying drawings, forming a part thereof.

Fig. 1 is a view in side elevation.

Fig. 2 is a top plan view.

I claim:—

The ornamental design for a lamp bracket, substantially as shown.

MAX ROTHBART.
